UNITED STATES PATENT OFFICE.

SAMUEL ORKIN, OF CHELSEA, MASSACHUSETTS, ASSIGNOR TO INTERNATIONAL BATTLESHIP COMPANY, OF BOSTON, MASSACHUSETTS, A CORPORATION OF MAINE.

GUN FIRING MECHANISM.

1,248,537.

Specification of Letters Patent. Patented Dec. 4, 1917.

Application filed April 23, 1917. Serial No. 164,276.

To all whom it may concern:

Be it known that I, SAMUEL ORKIN, a subject of Russia, and a resident of Chelsea, in the county of Suffolk and Commonwealth of Massachusetts, have invented certain new and useful Improvements in Gun Firing Mechanisms, of which the following is a specification.

This invention relates to devices or operating firing mechanisms of firearms and has for its object the provision of means for operating the firing mechanism of a fixed firearm at predetermined times.

The invention consists of a firearm preferably secured to a framework in a fixed position and a motor controlled endless chain adapted in its continuous movement in one direction to rotate a crank having a member pivoted thereto and reciprocable by the rotation thereof, the free end of which so contacts with the trigger of the firearm that the latter will be fired at each rotation of said crank.

The invention further consists in certain novel features of construction and arrangement of parts which will be fully understood by reference to the description of the drawings and to the claims hereinafter given.

30 Of the drawings:

Figure 1 represents an elevation of a firearm provided with a device for operating the firing mechanism thereof and embodying the principles of the present invention.

35 Fig. 2 represents a plan of the same, and

Fig. 3 represents a detail in elevation of the firing mechanism of said firearm.

Similar characters designate like parts throughout the several figures of the drawings.

In the drawings, 10 is a firearm herein shown as a revolver of the self-cocking type, the barrel of which has secured thereto a supplemental tubular member 11 shaped like the chase of a large caliber gun, this member 11 being adapted to extend through the port of a turret or similar member.

The revolver or firearm 10 is provided with the usual cylinder 12 adapted to receive cartridges and said cylinder 12 is rotated in the usual manner whenever this hammer 13 is cocked.

50 The hammer 13 is cocked by means of the member 14 pivoted at 15 and having the trigger arm 16 formed integral therewith.

Pivoted to the member 14 at 17 is the spring pressed member 18 having a finger 19 entering a notch 20 in the hammer 13.

When the trigger arm 16 is moved in the direction of the arrow *a* it is obvious that 60 the finger 19 will force the hammer 13 about its pivot 17 into cocked position.

As the hammer 13 approaches its cocked position the cam member 22 thereon will disengage the finger 19 from the notch 20 65 and permit the hammer 13 to be suddenly moved about its pivot 17 by means of the spring 23 and a cartridge in the cylinder will be exploded.

As the trigger arm 16 returns to its normal position in a direction opposite to that indicated by the arrow *a* the finger 19 will again be forced into the notch 20 by means of the spring 24 coacting with the member 18 all in an obvious manner. 70

The pivot 17 has also mounted thereon the spring pressed arm 21 engaging with the projections 25 on the cylinder 12, said arm being adapted to give a partial rotation of said cylinder 12 with every oscillation of the member 14 about its pivot 15. 75

Secured to the end of the arm 16 is a collar 26 upon which rests the forked end of a link 27, the opposite end of which is pivotally connected to the crank 28 secured 80 to the upper end of a revoluble shaft 29 mounted in bearings in the bracket 30 secured to a frame 31.

A spring 32 connects the arm 16 to the link 27, said spring insuring the return of 85 the trigger 16 to its normal position after each operation of the firing mechanism.

The revoluble shaft 29 has secured to its lower end a sprocket wheel 33 the teeth of which mesh with an endless chain 34 supported upon the wheels 35, 36, and 37. 90

The wheel 35 is secured to and rotates with the shaft 38 of a motor 39 shown in the drawings as an electric motor in a circuit 40 provided with a battery 41 and a switch 42. When the switch 42 is on, the motor 40 will drive the chain 34 in the direction indicated by the arrow *b*. 100

The firearm 10 is rigidly secured by the bolts 44 to the bracket 45 secured to the frame 31. The rotation of the crank 28 will cause the link 27 to move the trigger arm 16 to the left of Figs. 1 and 2, and thereby cause the hammer to be cocked and then released as heretofore described. 110

The device is particularly applicable to toy battleships in which it is desired that the guns protruding from the various turrets should be fired at predetermined times.

5 It is obvious that when the chain is moving the continued rotation of the crank will cause the firing of the revolver until the last cartridge in the cylinder is exploded.

It is believed that the construction and 10 operation will be fully understood from the foregoing description.

Having thus described my invention, I claim:

1. The combination of a firearm provided with a hammer; means for rigidly securing said firearm to a stationary member; a hammer operating member; a reciprocating member for operating said hammer in its movement in one direction; a revolute 20 crank for imparting motion to said reciprocating member; a spring secured thereto at one end and having its other end secured to said hammer operating member,

2. The combination of a firearm provided 25 with a hammer; means for rigidly securing said firearm to a stationary member; a hammer operating member; a reciprocating member for operating said hammer in its movement in one direction; and a spring secured at one end to said reciprocating member and at the other end to said hammer operating member.

3. The combination of a firearm provided 35 with a hammer; means for rigidly securing said firearm to a stationary member; a hammer operating member; a reciprocating forked member straddling said hammer op-

erating member and adapted to operate said hammer in its movement in one direction; and a spring secured at one end to said reciprocating member and at the other end to said hammer operating member.

4. The combination of a firearm provided with a hammer; means for rigidly securing said firearm to a stationary member; a hammer operating member; a reciprocating member for operating said hammer in its movement in one direction; a revolute crank for imparting motion to said reciprocating member; a revolute shaft to which said crank is secured; a bearing therefor mounted on said stationary member; a sprocket wheel secured to said shaft; and a driven endless belt for driving said wheel.

5. The combination of a firearm provided 55 with a hammer; means for rigidly securing said firearm to a stationary member; a hammer operating member; a reciprocating member for operating said hammer operating member in its movement in one direction; a revolute crank for imparting motion to said reciprocating member; a revolute shaft to which said crank is secured; a bearing therefor mounted on said stationary member; a sprocket wheel secured to said 65 shaft; an endless belt for driving said wheel; and an electric motor for moving said chain.

Signed by me at Washington District of Columbia this 28th day of March, 1917.

SAMUEL ORKIN.
